(57) **CLAIM**

The ornamental design for a mouse trap alert assembly as shown and described.

DESCRIPTION

FIG. 1 is a top left perspective view of a mouse trap alert assembly showing my new design.

FIG. 2 is a top view thereof.

FIG. 3 is a bottom view thereof.

FIG. 4 is a left view thereof.

FIG. 5 is a right view thereof.

FIG. 6 is a rear view thereof.

FIG. 7 is a front view thereof; and,

FIG. 8 is a top left perspective view thereof showing a mouse trap inserted into the mouse trap alert assembly. The broken lines of equal length in the drawings depict portions of the mouse trap alert assembly that form no part of the claimed design.
